L. STEINBERGER

INSULATOR

Original Filed Jan. 17, 1918

UNITED STATES PATENT OFFICE.

LOUIS STEINBERGER, OF BROOKLYN, NEW YORK.

INSULATOR.

Application filed January 17, 1918, Serial No. 212,341. Renewed June 11, 1923.

To all whom it may concern:

Be it known that I, LOUIS STEINBERGER, a citizen of the United States, and a resident of the borough of Brooklyn, county of Kings, city and State of New York, have invented certain new and useful Improvements in Insulators, of which the following is a specification.

This invention relates to insulators of the compression type and embodies a new construction by means of which the insulator body and strain members may be quickly assembled and disassembled.

One of the objects of my invention is to provide an improved insulator having a body of insulating material which is entirely separate from but which may be readily connected to the respective strain members.

Another object of the invention is to provide an improved construction by means of which a new insulating body may be readily substituted for one which has become worn or broken in use.

Other objects will appear from the subjoined specification and claims.

Referring to the drawings:

Fig. 1 is a side elevation of an insulator construction embodying my invention.

Fig. 2 is a section on line 2—2 of Fig. 1. Fig. 3 is a plan view of the end of an insulator showing the construction and formation thereof.

Fig. 4 is a section partly broken away of a modified form of construction showing an insulating body with metallic re-enforcement on the end thereof.

Fig. 5 is a plan view of the metallic re-enforcement, a section of which is illustrated in Fig. 4.

Fig. 6 is a sectional view on line 6—6 of the metallic re-enforcement shown in Fig. 5.

In the drawings in which like reference characters indicate like parts, 10 is an insulating body, the side 10' of which is preferably provided with the formation shown which insures a longer surface for the travel of the electric current over the insulating body than would otherwise be the case should an insulating body having a smooth cylindrical surface be employed.

The insulating body is provided at each end with a formation which consists of a circular groove 13 which is formed therein and two grooves 14 and 14' which extend radially from said circular groove to the

outer surface of the insulating body, these latter grooves being situated diametrically opposite to each other.

The groove formation as described and shown results in the formation of two outer walls or ridges 15 and 16 and an inner solid projection 17 on the ends of the insulating body.

The strain members are so constructed that they may be interlocked one with the other and to this end one of the strain members 20 is integral and the other strain member 21 is provided with two parts 22 and 23, the free ends of each of the leg portions of each of these parts having screw threads 24 and 25 formed thereon and are secured to each other by nuts 26 and 26' as shown.

Bridge portions 30 and 31 connect the leg portions 32, 33 and 34, 35 of the strain members, the bridge portions consisting of rings 36 and 37 and radial projections 36', 36'' and 37', 37'' extending opposite to each other, which projections offset the legs from the rings.

The rings and the offset projections of the bridge pieces are so shaped as to fit closely in the circular groove and radial grooves provided in the ends of the insulators when the strain members are mounted thereon.

As will be seen, the radial projections fitting in the radial grooves will prevent the strain members from turning axially on the insulating body, and the consequent short circuiting should the strain members touch each other.

In some instances, I have found it advantageous to re-enforce each end of the insulating body by molding thereto a metal plate 50 as shown in Fig. 4. The metal plate is provided on its outer surface with a circular groove 51 and with radially extending grooves 52 and 53 as shown, and they are of such shape and dimensions as to readily fit the ring and offset projections of the strain members.

The insulator is assembled by first interlocking the strain members as shown and then connecting the legs of the two part strain member together by means of the nuts.

An insulating body of any preferred shape which is provided with grooved ends as shown and described is then fitted between the bridge portions of the strain members, the rings and offset projections of the bridge portions of the strain members fitting into

the circular groove, and the radial grooves respectively in the ends of the insulator. Such an insulator is very efficient and may be readily mounted and dismounted and also 5 a new insulator body may be substituted for a broken insulator body without having to remove the entire insulator. The duplication of parts in the manufacture thereof results in much convenience and in much 10 saving of cost of manufacture.

The neck portion 60 of the body part which is to receive the metal reenforcing plate may be made angular in horizontal 15 cross section so as to prevent the metal reinforcement from twisting out of position.

The insulating member may be of any suitable material such as porcelain or glass, but I prefer to use the material known in the art as "electrose," and the remaining 20 parts are formed of any suitable metal or alloys thereof.

As changes of construction could be made within the scope of my invention, it is intended that all matter contained in the above 25 description or shown in the accompanying

drawings shall be interpreted as illustrative and not in a limiting sense.

Having now described my invention what I claim as new and desire to secure by Letters Patent is:

1. In a device of the kind described, an insulator body provided with ring shaped grooves in the opposite faces thereof and radial grooves in the surface of the insulator projecting from said ring-shaped grooves. 35

2. In a device of the kind described a body of insulating material having ring-shaped grooves in the opposite faces thereof, and grooves extending radially therefrom, the radial grooves in one face being substantially at right angles to the radial grooves in the other face. 40

In witness whereof, I have hereunto set my hand at the borough of Manhattan, city and State of New York, this fifteenth day 45 of January, 1918.

LOUIS STEINBERGER.
In presence of—
C. C. BILLINGS,
ZITA M. GRAHAM.
